UNITED STATES PATENT OFFICE.

GILBERT H. TEGELBERG, OF INGLEWOOD, CALIFORNIA.

ROCKING-HORSE TOY.

Application filed November 1, 1926. Serial No. 145,566.

My invention is a rocking horse toy having a springing motion up and down due to a spring action and also a direct motion forward, together with steering mechanism.

5 An object of my invention is the construction of a rocking horse toy for children, of the type that the seat has an up and down motion with a spring to force the seat upwardly, the child's weight forcing it downwardly.

10 Another object of my invention is the construction of a rocking horse toy which will have a motion forward without any direct driving mechanism, the up and down 15 spring of the child giving the impetus forward and having a pawl and ratchet acting to prevent the rearward movement of the horse. I also provide a steering device operated by the child's feet to guide the horse.

20 My rocking horse toy is preferably constructed by having a longitudinal frame with a single rear wheel having a pawl and ratchet operating therewith; and preferably two front wheels are connected by a king 25 bolt to the frame and may be connected to steer the device. The horse structure with a seat is pivotally connected to the front of the frame and has a compression spring connected thereto to counter balance the 30 child's weight and thus give an up and down swinging motion. A foot lever operated by the child is utilized to steer the front wheels; a snubber prevents excessive upper rebound.

35 My invention is illustrated in the accompanying drawings, in which:

Figure 1 is a side elevation of my toy showing the position of the child seated thereon,

40 Figure 2 is a rear perspective.

In constructing my invention I desire to make same as simple as possible and, therefore, build a relatively cheap toy. I construct a longitudinal frame 1 preferably 45 made by a slat or board. This has a bracket 2 connected at its rearward end in which the rear wheel 3 is journaled. There is preferably an opening 4 in the board for the top of the wheel to extend therethrough in order 50 to lower the frame close to the ground. A ratchet 5 is carried by the wheel and a pawl 6 is connected to the frame and pressed by a spring 7 into an engagement with the ratchet.

55 A king pin 8 is connected to the forward end of the frame and a crossbar 9 is pivot-

ally connected to such bolt. Wheels 10 are suitably connected to the outer ends of the bar and may be rigidly connected to such ends.

60 The springing horse is constructed and mounted substantially as follows: A hinge 11 is secured to the forward end of the frame and the slat 12 is connected to the hinge. This slat supports a horse-shaped 65 structure 13, this simulating the neck and head of a horse, and has a saddle 14 connected thereto, this saddle preferably having a pommel 15 which the child may grasp. A compression spring 16 of the coil type is 70 connected between the frame 1 and the slat 12, there preferably being studs 17 which center the spring. The snubber strap 18 secured to the rear end of the frame and the slat 12 prevents too great an upward rebound.

75 The steering device is constructed as follows: A foot lever 19 is connected to the slat by a pivot pin 20 and is positioned to be comfortably engaged by the child's feet. 80 Steering cords 21 connect corresponding ends of the lever and the crossbar 9.

85 The saddle is adjustable on the slat 12 preferably by having the lower part of the saddle with a groove 22 to allow sliding motion and having a bar 23 connected thereto across the bottom of the slat provided with a thumb screw 24 to clamp the saddle.

90 The manner of function of my rocking horse toy is substantially as follows: It will be seen that a child may comfortably sit on the saddle with his feet on the steering lever and he may swing up and down so that the spring is alternately compressed and expanded, oscillating the slat 12 up and down 95 and giving the child an up and down rocking motion. Due to the impetus of the rocking motion the toy is forced in a forward direction but the rear wheel 3 is prevented from having a reverse motion by means of the pawl and ratchet device. In order to steer the toy the child operates the foot lever one way or the other, pulling on the cords 21, and thus pivoting the bar 9 on the king pin. As above mentioned the strap 18 prevents excessive rebound.

100 Although I have shown a toy of a simple character it is to be understood that it may be elaborated in details and various features altered.

105 The principle of my invention may be changed without departing from the spirit

thereof as set forth in the description of the drawings and claims.

I claim:

1. A rocking horse toy comprising in combination, a longitudinal frame having a pivotally connected crossbar, a wheel mounted on the rear end of the frame for free rotary movement in one direction, wheels on the crossbar one at each end thereof, a slat hingedly connected to the frame adjacent the crossbar, a saddle mounted on the slat, and a spring connecting the slat and the frame.

2. A rocking horse toy as claimed in claim 1, a foot lever pivotally connected to the slat, and means connecting said lever and the crossbar to allow steering.

3. A rocking horse toy comprising in combination, a longitudinal frame having a wheel at the rear end, a ratchet on said wheel, a pawl on the frame engaging the ratchet, a crossbar pivotally connected to the forward end of the frame, a slat hingedly connected to the forward end of the frame

and having a saddle thereon, a compression spring between the frame and the slat, and means operatively connected to the slat to actuate the crossbar to steer the toy.

4. A rocking horse toy as claimed in claim 3, the saddle being slidably mounted on the slat and having means to clamp same in adjusted position.

5. A rocking horse toy comprising in combination, a longitudinal frame having a wheel at the rear end, a pawl and ratchet connection with said wheel, a crossbar pivotally connected to the forward end of the frame and having wheels in each end, a slat hingedly connected to the forward end of the frame and having a seat slidably mounted thereon, a compression spring between the slat and the frame, a foot lever pivotally connected to the slat and flexible connections between said lever and the crossbar to steer the toy.

In testimony whereof I have signed my name to this specification.

GILBERT H. TEGELBERG,
